(57) **CLAIM**

The ornamental design for a helical threaded fishing weight, as shown and described.

DESCRIPTION

FIG. 1 is a right side perspective view of a first embodiment for a helical threaded fishing weight showing my new design; FIG. 2 is a left side perspective view of the first embodiment thereof;

FIG. 3 is a right side view if the first preferred embodiment shown with environmental subject matter.

FIG. 4 is a left side view of the first preferred embodiment thereof;

FIG. 5 is a front side view of the first preferred embodiment thereof;

FIG. 6 is a right side view of the first preferred embodiment thereof;

FIG. 7 is a rear side view of the first preferred embodiment thereof;

FIG. 8 is a left side view of a second preferred embodiment thereof;

FIG. 9 is a front side view of the second preferred embodiment thereof;

FIG. 10 is a right side view of the second preferred embodiment thereof;

FIG. 11 is a rear side view of the second preferred embodiment thereof;

FIG. 12 is a left side view of a third preferred embodiment thereof;

FIG. 13 is a front side view of the third preferred embodiment thereof;

FIG. 14 is a right side view of the third preferred embodiment thereof;

FIG. 15 is a rear side view of the third preferred embodiment thereof;

FIG. 16 is a left side view of a fourth preferred embodiment thereof;

FIG. 17 is a front side view of the fourth preferred embodiment thereof;

FIG. 18 is a right side view of the fourth preferred embodiment thereof;

FIG. 19 is a rear side view of the fourth preferred embodiment thereof;

FIG. 20 is a top side view of the fourth preferred embodiment thereof;

FIG. 21 is a bottom side view of the fourth preferred embodiment thereof;

FIG. 22 is a top side view of the third preferred embodiment thereof;

FIG. 23 is a bottom side view of the third preferred embodiment thereof;

FIG. 24 is a top side view of the second preferred embodiment thereof;

FIG. 25 is a bottom side view of the second preferred embodiment thereof;

FIG. 26 is a top side view of the first preferred embodiment thereof; and,

FIG. 27 is a bottom side view of the first preferred embodiment thereof.

The broken lines in FIG. 3 depict environmental subject matter only and form no part of the claimed design.
